DESIGN FOR A PINCUSHION

Herman D. Bernstein and Ruth Bernstein,
Brooklyn, N. Y.

Application August 19, 1941, Serial No. 102,947

Term of patent 3½ years

To all whom it may concern:

Be it known that we, Herman D. Bernstein and Ruth Bernstein, both citizens of the United States and both residents of Brooklyn, New York, in the county of Kings, and State of New York, have invented a new, original, and ornamental Design for a Pincushion, of which the following is a specification, reference being had to the accompanying drawing, forming a part thereof.

In the drawing

Fig. 1 is a front elevational view of a pincushion, showing our new design.

Fig. 2 is a side elevational view of the same.

Fig. 3 is a rear elevational view of the same.

We claim:

The ornamental design for a pincushion, as shown.

HERMAN D. BERNSTEIN.
RUTH BERNSTEIN.
